UNITED STATES PATENT OFFICE.

THOMAS J. COPE, OF PHILADELPHIA, PENNSYLVANIA.

ELEVATING-JACK.

No. 827,505.

Specification of Letters Patent.

Patented July 31, 1906.

Application filed October 21, 1905. Serial No. 283,765.

To all whom it may concern:

Be it known that I, THOMAS J. COPE, a citizen of the United States, residing in the city and county of Philadelphia, State of Pennsylvania, have invented a new and useful Elevating-Jack, of which the following is a specification.

My invention consists of an elevating-jack comprising a follower, a head for operating the same, and means for holding it in adjusted position relatively to the differences in extent of the load imposed upon it.

It also consists of means for vertically adjusting the head so that a greater range of vertical motion may be obtained for action upon the follower.

It also consists of details of construction, as will be hereinafter set forth.

Figure 1 represents a perspective view of an elevating jack embodying my invention. Figs. 2 and 3 represent vertical sections thereof, showing certain members of the device in different positions. Fig. 4 represents a section of a portion at a right angle to that shown in Fig. 3.

Similar letters of reference indicate corresponding parts in the figures.

Referring to the drawings, A designates a standard of the jack, and B the base thereof. C designates a cam-head which is mounted by the axle D on the standard A, it being noticed that the sides of the standard are slotted, forming a series of teeth E, one above the other, on which the axle D may be placed, thus providing for placing said cam-head C at different altitudes.

F designates a follower which is fitted within and guided by the walls of the standard A, and carries at its lower end the roller G, which is adapted to ride upon the periphery of said cam-head C, it being noticed that said periphery is provided with a number of recesses H, into either of which said roller is adapted to drop and rest, as most plainly shown in Fig. 2. The periphery of the cam-head is also provided with ratchet-teeth J, which are preferably sunken below the portion of the periphery containing the recesses H and adapted to be engaged by the dog or pawl K, which has its bearings L on the lower portion of the follower F.

In the periphery of the cam-head is a series of openings M, either of which is adapted to receive the end of the rod or handle N, where- 55 by said head may be rotated.

The operation is as follows: For elevating an object of ordinary weight the pawl K is raised clear of the ratchet-teeth J and thrown against the follower F, so as to be inoperative, as shown in Fig. 2. The rod N is now inserted in one of the openings M as a handle and manipulated, whereby rotary motion is imparted to the cam-head C, and then inserted in another of said openings, thus further rotating said cam-head, the swell of the latter with which the roller G is in contact then causing the ascent of the follower F, it being noticed that when the proper height of said follower is reached said roller occupies the respective recess H in the cam-head below it, (see Fig. 2,) and the weight superimposed on said follower causes said roller to retain its position in said recess, preventing the descent or dropping of the follower, and consequently of the load. The pawl or dog may now be engaged with the ratchet, if so desired; but when the weight to be elevated is heavy said pawl or dog K is primarily lowered, so that it may ride over the ratchet as the cam-head rotates, and when the latter ceases engagement with the respective tooth of said ratchet thus interlocking the cam-head and preventing any possible returning motion of the latter, while most firmly controlling the follower F in its elevated position. When the jack is to be lowered, the dog or pawl K is thrown up, thus clearing the ratchet-teeth J, when by proper manipulation of the rod N the cam-head C may be rotated in reverse direction, causing the roller G to ride upon the narrow part of said head, thus lowering the follower.

In order to assist in supporting the follower when in elevated position, I provide the same with a series of openings P, one below the other, as shown in Figs. 2 and 3, in either of which may be placed the pin Q, the same being adapted to rest upon the top of the standard, as shown in Fig. 4, the effect of which is evident, it being seen that when the follower is raised to a certain height and it is desired to increase said height the pin Q may be inserted in one of the lower openings P or in the lowermost opening and rested on the top of the standard, after which the cam-head is lowered, its axle B then being placed on one of the teeth E at greater height or at the greatest height, when the cam-head may be again rotated, thus elevating the follower to a greater extent.

Having thus described my invention, what I claim as new, and desire to secure by Letters Patent, is—

1. In an elevating-jack, a follower and an elevating-head therefor, the latter being provided with a variable surface, the same having a series of separate openings therein and a removable handle adapted to be fitted in either of the latter.
2. In an elevating-jack, a follower and an elevating-head therefor, the latter being adapted to have said follower engage thereon, and being provided with separate means for interlocking said follower therewith comprising a series of recesses in the periphery of said head either of which is adapted to receive the base of said follower, a ratchet on said periphery and a pawl on said follower, said pawl being adapted to engage either tooth of said ratchet.
3. An elevating-jack having a follower, an elevating-head therefor, the latter being adapted to have said follower engage therewith, a series of recesses on said head in

either of which said follower may be seated, a ratchet on said head, and a pawl on said follower which is adapted to engage with either member of said ratchet.

4. In an elevating-jack, a standard, a follower thereon, a rotatable elevating-head mounted on said standard and adapted to engage said follower, a ratchet on said head and a pawl on said follower adapted to engage a tooth of said ratchet.

5. An elevating-jack consisting of a standard, a series of teeth on the latter one above the other, a follower on said standard, said follower having a series of openings therein one above the other, an elevating-head adapted to be mounted on either of said teeth and engage said follower to raise it and a pin adapted to be passed through either of said openings and rest on said standard.

THOMAS J. COPE.
